UNITED STATES PATENT OFFICE.

FRANK A. DREES, OF PAWHUSKA, OKLAHOMA, ASSIGNOR, BY MESNE ASSIGNMENTS,
OF ONE-HALF TO FRED D. TURNER, OF PAWHUSKA, OKLAHOMA.

FITTING.

Application filed August 1, 1924. Serial No. 729,577.

This invention relates to a pipe fitting, the general object of the invention being to provide socket members in the walls and floor of a building to which gas and other lines are connected and to which gas stoves and the like can be connected by pipes which are detachably connected with the socket members and can be easily removed when the stove or other device is not being used.

Another object of the invention is to provide hinge covers for the socket members which will close the same when the connecting pipes have been removed and thus make a neat appearance and prevent dirt and dust getting in the parts.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a sectional view of a socket member.

Figure 2 is an elevation thereof.

Figure 3 is a view of a T-coupling.

Figure 4 is a sectional view showing how the invention is arranged in a wall between two rooms.

Figure 5 is a view of a nipple for use with a floor plug.

Figure 6 is a sectional view showing the floor arrangement in use.

Figure 7 is a view of an elbow.

Figure 8 is a sectional view showing the elbow arrangement in use.

In these views, 1 indicates a socket which is entirely screw threaded and is formed with a face plate 2, a hinged flap or door 3 being arranged to cover the end of the socket member when the same is not being used. The socket member is adapted to be placed in a hole formed in the base board or other part of a wall or in the floor of a building with the face plate overlapping the wall face or floor. The pipes leading the gas to the socket member has a part threaded to fit into the socket and the interior of this part of the pipe is also threaded to receive a pipe or tube which is adapted to lead the

gas to the stove or other fixture. Figure 3 shows a T 4 which is used to connect two socket members to a supply pipe 5. These socket members are placed in the walls A of two rooms and two of the ends of the T are threaded, as at 5', to engage the threads in the socket members and its nipple 6 is interiorly threaded to receive the threaded end of the supply pipe 5. As will be seen the T is located between the partition walls and is therefore hidden from view. Its ends are interiorly threaded, as at 7, to receive the threaded end of a pipe or tube 8 which is adapted to be connected to a stove or other fixture. When the fixture is not being used the pipe 8 is removed and a plug, such as shown at 9, is threaded in the coupling and then the flap 3 is closed, as shown in the left hand part of Figure 4. When the device is to be placed in a floor, a straight nipple 10 is used, as shown in Figures 5 and 6, the threaded end of this nipple engaging the socket member which is placed in the floor C and this nipple 10 is connected with the supply pipe 5'. Its threaded end is threaded interiorly to receive the pipe 8' which is connected with the stove or other fixture.

When but one socket member is used, as in Figure 8, an elbow pipe 11 is used to connect the socket member with the supply pipe, as shown in Figure 8. This elbow is threaded interiorly to receive the pipe 8'' which is connected with the stove or other fixture and is also connected with the supply pipe 5''.

From the foregoing it will be seen that the connections are all hidden from view and the connecting pipe can be easily attached to the supply pipes or detached therefrom so that when a stove or fixture is not being used it and its connecting pipe can be removed. A plug 9 is then inserted and the flap closed so that the appearance of the room is not marred by protruding pipes and the parts are protected from dirt and dust.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In a pipe fitting, a face plate having an

internally threaded socket integral therewith, the said face plate being adapted to engage the surface of a wall or floor through which the socket passes, a door member 5 hinged to the face plate for normally closing one end of the socket, a T-member connected in a pipe line having one end threaded in the socket, the said end being also internally

threaded for the reception of a small pipe whereby the plate forms no part of the 10 pipe line but is merely a threaded support for the pipe at a point where a smaller pipe is connected into the main pipe line.

In testimony whereof I affix my signature.

FRANK A. DREES.
